(57) CLAIM

The ornamental design for an insect control device, as shown and described.

DESCRIPTION

FIG. 1 is a drawing illustrating a perspective view taken from the front, top, and right side of an insect control device illustrating our new design;

FIG. 2 is a drawing illustrating a right side elevation view thereof, the left side elevation view being identical to the illustrated right side elevation view;

FIG. 3 is a drawing illustrating a front elevation view thereof, the rear elevation view thereof being identical to the illustrated front elevation view;

FIG. 4 is a top plan view thereof;

FIG. 5 is a bottom plan view thereof; and,

FIG. 6 is a perspective view taken from the bottom, front, and right side of the insect control device.
